Shinichiro Sito,

UNITED STATES PATENT OFFICE.

SHINICHIRO SITO, OF PRAIRIE CITY, OREGON.

LAMP-SHADE.

1,271,091.

Specification of Letters Patent.

Patented July 2, 1918.

Application filed February 27, 1918. Serial No. 219,475.

To all whom it may concern:

Be it known that I, SHINICHIRO SITO, not a citizen of the United States, but of Japan, residing at Prairie City, in the county of 5 Grant and State of Oregon, have invented certain new and useful Improvements in Lamp-Shades, of which the following is a specification.

This invention relates to an improvement 10 in lamp shades, and more particularly to shades for electric lamps.

The object of the invention is to provide a simply constructed, cheap lamp shade which, while presenting a pleasing appearance and 15 which may be changed quickly to vary the color of the light radiated therefrom.

Another object is to provide a device of this character which, when removed from the lamp and not in use may be collapsed 20 into a very small space to facilitate its storage and transportation and which, when applied will open up readily into the position desired for use.

With the foregoing and other objects in view, which will appear as the description proceeds, the invention resides in the combination and arrangement of parts and in the details of construction hereinafter described and claimed, it being understood 30 that changes in the precise embodiment of the invention herein disclosed may be made within the scope of what is claimed without departing from the spirit of the invention.

35 In the accompanying drawings:—

Figure 1 represents a bottom plan view of the shade constituting this invention shown in open operative position,

Fig. 2 is an end elevation thereof,

40 Fig. 3 is a plan view of the shade detached and collapsed, and

Fig. 4 is an edge view of the collapsed shade.

In the embodiment illustrated, the shade 45 constituting this invention comprises a pair of semi-circular members 1 and 2, preferably constructed of cardboard or celluloid strips, although obviously they may be composed of aluminum or other material if 50 found desirable. The ends of these strips are hingedly connected as shown at 3, flexible strips of muslin or the like being preferably used for the hinges, which, while cheap in construction, is effective in operation and 55 will last for a considerable time.

These semi-circular strips or members 1

and 2 have secured thereto a collapsible shade member 4 composed of paper or similar material of any suitable or desired color, which is crimped as shown at 5 to be folded 60 into a small space when collapsed as shown in Fig. 4, and which will open up into the form shown in Figs. 1 and 2, presenting when so opened, a very pleasing appearance, a uniform configuration being imparted to 65 the folds so that substantially diamond shaped figures are produced when the shade is in open operative position.

Attaching clips 6 are carried by each of the members 1 and 2 and are here shown 70 composed of fine wire strips, each folded intermediately of its ends and bent laterally to form a U-shaped clamping member 7, the arms 8 extending inwardly between each of the supporting members 1 or 2 and the 75 shade proper 5, said arms being slidably mounted so that the clips may be adjusted to fit lamp shades S of varying diameters. As shown, these arms 8 are brought together at their inner ends and twisted as shown at 80 9 so that all danger of the clips slipping out and becoming lost is avoided.

As shown in the accompanying drawings, securing bands 10 are used for attaching the members 1 and 2 midway their ends to the 85 shade 4 and also for connecting arcuate reinforcing sections 11 to said members. The sections 11 extend partially around the members 1 and 2 as is shown clearly in Fig. 4 and the legs of the clips 6 are slidably mounted 90 between these sections 11 and the members by which they are carried.

In the use of this improved shade, the members 1 and 2 are opened outwardly in opposite directions into the position shown 95 in Figs. 1 and 2 and the hooked portions 7 of the clips 6 are engaged around the edges of a lamp shade S at diametrically opposite points thereby connecting the detachable shade 4 to the shade S which is usually of 100 opaque glass and is commonly used for electric lights. By making the members or clips 6 extensible obviously, the shade 4 may be attached to a porcelain shade or other support of varying diameters.

When it is desired to remove shade 4, one of the clips 6 is slid outwardly to disengage its hook 7 from the shade S and the shade 4 may then be removed and folded into the position shown in Fig. 4 so that it will 110 occupy a minimum amount of space when stored.

By so constructing these shades, any desired number may be kept in stock and of varied colors so that when desired a red, green, blue, or other color may be used at the will of the owner, and when not in use, may be collapsed and placed in a small space out of the way.

From the foregoing description, taken in connection with the accompanying drawings, the advantages of the construction and of the method of operation will be readily apparent to those skilled in the art to which the invention appertains and while I have described the principle of operation of the invention together with the device which I now consider to be the best embodiment thereof, I desire to have it understood that the device shown is merely illustrative and that such changes may be made as are within the scope of the claimed invention.

I claim:—

1. A shade of the class described comprising a pair of semi-circular frame sections, hingedly connected at their ends, a collapsible shade secured to said sections, and means for detachably connecting said sections intermediately of their ends to a supporting structure.
2. A collapsible lamp shade comprising a pair of semi-circular frame sections hingedly

connected at their ends, a collapsible shade structure foldable to conform to the shape of the sections when in operative position and adapted to be opened into semiispherical form when open, and means for connecting said frame sections to a lamp shade.

3. A lamp shade comprising a pair of semi-circular frame sections hingedly connected at their ends, a semispherical shade connected with said sections and foldable to conform to the shape of said sections when collapsed, and means for adjustably and detachably connecting said frame sections to a support.

4. A lamp shade comprising a pair of semi-circular frame sections hingedly connected at their ends, and reinforcing superposed arcuate strips carried by said sections and secured thereto, a shade semispherical in shape when opened, and collapsible to conform to the shape of the sections when closed, and adjustably connected elements slidably mounted between the frame sections and their reinforcing members.

In testimony whereof I affix my signature in presence of two witnesses.

SHINICHIRO SITO.
